(57) CLAIM

The ornamental design for an animal grooming garment, as shown and described.

DESCRIPTION

FIG. 1 is a front perspective view of an animal grooming garment, showing my new design;

FIG. 2 is a front elevation view thereof;

FIG. 3 is a rear elevation thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict the bounds of the claimed design of the animal grooming garment that form no part of the claimed design.

1 Claim, 5 Drawing Sheets
